(57) **CLAIM**

The ornamental design for a slide holder, as shown and described.

DESCRIPTION

FIG. 1 is a top perspective view of a slide holder; FIG. 2 is a bottom perspective view thereof; FIG. 3 is a top plan view thereof; FIG. 4 is a bottom plan view thereof; FIG. 5 is a left side elevation view thereof; FIG. 6 is a right side elevation view thereof; FIG. 7 is a front elevation view thereof; FIG. 8 is a rear elevation view thereof; FIG. 9 is a section view of FIG. 3 along section lines 9-9; and, FIG. 10 is a section view of FIG. 3 along section lines 10-10. The broken lines in the drawings depict portions of the slide holder that form no part of the claimed design.
